UNITED STATES PATENT OFFICE

FRANK CLARKE, OF ST. LOUIS, MISSOURI, ASSIGNOR TO PITTSBURGH PLATE GLASS COMPANY, A CORPORATION OF PENNSYLVANIA

ORNAMENTAL GLASS

Application filed May 19, 1932. Serial No. 612,287.

The invention relates to ornamental glass designed particularly for use in signs, but not limited to such use. It has for its objects the provision of a glass construction easily and cheaply produced and presenting an unusual and pleasing appearance, when viewed from the front. The invention is illustrated as applied to a single letter, but it will be understood that combinations of letters and numbers may be used as well as a wide variety of ornamental designs. One embodiment of the invention is illustrated in the accompanying drawing, wherein:

Figure 1 is a section on the line I—I of Fig. 2. Fig. 2 is a front elevation of the construction. Fig. 3 is a front elevation of the glass plate which has been provided with its ornamentation in relief. Fig. 4 is a section on the line IV—IV of Fig. 3. Fig. 5 is a similar section, but with its rear face provided with color films. And Fig. 6 is a section through the mirror plate employed back of the face plate.

Referring to the drawing, 1 is a frame of any suitable type which carries the glass plates 2 and 3 and the backing 4 of any suitable material for holding the glass plates in position. The plate 2 is shown as provided with a very simple design, namely the letter E, but it will be understood that the principle is applicable to more complicated designs. The design is preferably formed on the rear face of the plate 2 by sand blasting. This is accomplished by coating the border portion 5 and the letter portion 6 with a material resistant to the action of a sand blast, preferably a rubber composition. After the plate is thus coated, a sand blast is applied in the usual way, which sand blast removes the portion 7 of the plate surrounding the letter, thus leaving the portions 5 and 6 in relief, as indicated in Fig. 5. The rubber coating is then removed and a further light application of the sand blast is made to roughen the rear surface of the portions 5 and 6, so that they will take and hold the paint or coloring more effectively than would the polished glass surface.

The plate is now ready for coloring, which may be done in various ways by hand or otherwise. If a three-color design is desired, the coats 8, 9 and 10 will all be of different colors. For instance, the border 8 may be blue, the letter coating 10 may be red and the background coating 9 may be yellow. The

back plate 3 is provided on its rear face with a coating 11 of silver or other suitable reflecting material, such as cadmium, lead sulphide or quick silver. The parts are then assembled, as indicated in Fig. 1 with the mirror plate 3 behind the face plate 2. This arrangement gives a design of unusual and pleasing appearance. The forming of the design in relief on the back of the plate 2 makes it stand out more clearly than is the case where a design is merely painted on the back of a glass sheet. The use of the mirror behind the face plate brightens the appearance of the design and renders it more attractive. The roughening of the rear surface of the face plate, due to the sand blasting, also improves the appearance as the reflection is softened and the application of the coloring material is much more uniform than where such coloring is applied to a polished glass surface. The colors employed are not opaque, but are relatively translucent so that a certain amount of mirror reflection is noticeable through such colors. As a result the design stands out clearly even in a relatively subdued light.

The term "relief" refers to the formation of the design either above the level of the background or below it, the general effect being the same in both cases.

What I claim is:

In combination, a glass plate having its rear face provided with a design in relief, said design and the area of the rear face surrounding it being roughened, and a second sheet of glass having its front face in engagement with the rear face of the first sheet and provided upon its other face with a metallic reflecting coating, said design and the surrounding area being covered by colored coatings applied thereto which are of contrasting color and are translucent to permit the reflecting coating to reflect light therethrough.

In testimony whereof, I have hereunto subscribed my name this 13th day of May, 1932.

FRANK CLARKE.
